APPARATUS FOR CLEANING ROAD SURFACES

Thomas Harris and Charles C. Plumb,
Warwick, R. I.

Application June 25, 1952, Serial No. 295,462

9 Claims. (Cl. 51—8)

1

This invention relates to a method and apparatus for cleaning road surfaces, particularly for removing oil, grease, and gasoline deposits from road surfaces.

The accumulation of oil, grease, and gasoline deposits on road surfaces resulting from the droppings of motor vehicles, particularly at stop intersections, clover-leaf turn-outs, bridges, and other places where traffic is slowed down and is most congested, makes a highway hazard, particularly when such deposits are wet, which is the cause of many serious accidents, many of which result in death. Such oil, grease, and like deposits become imbedded in the road surface and are not efficiently removed by the usual road flushing and sweeping.

An object of the invention is to provide for the quick and efficient removal of oil, grease, and the like deposits from road surfaces.

A more specific object of the invention is to provide for the removal of oil, grease, and the like deposits from road surfaces by a cutting action thereon.

Another object of the invention is to provide for the removal of oil, grease, and the like deposits from road surfaces by directing an abrasive stream thereon at an angle to the road surface, which will have a tendency to cut and raise the said deposits from the road surface.

Another object of the invention is to provide an apparatus operable for the removal of oil, grease, and like deposits from road surfaces.

Another object of the invention is to provide an apparatus of the above character having a plurality of cleaning jets controllable from a common location readily accessible to the operator of the apparatus.

With these and other objects in view, the invention consists of certain novel features of construction as will be more fully described and particularly pointed out in the appended claims.

In the accompanying drawings:

Figure 1 is a side elevational view of a road cleaning apparatus embodying one form of the invention; and

Figure 2 is a plan view of a portion of the apparatus shown in Figure 1 looking thereon in the direction of the arrows on line 2—2 of Figure 1.

In carrying out our invention, we provide for the removal of oil, grease, and the like deposits from road surfaces by a cutting action such as by the use of a sand blasting action thereon. The sand blasting stream is directed on the area to be cleaned at such an angle to the road surface as to tend to cut and raise the contaminant from

the road surface and direct it and the spent abrasive to a supply for reuse if conditions are such as to permit reuse of the abrasive. The angle at which the abrasive stream is directed on the deposits will depend upon the type of road surface, a concrete road surface requiring a different angle of attack than a black top or rubber composition road surface. The sand blast may consist of the usual air under pressure, or may employ steam as the abrasive carrier when conditions and locations are found to be favorable for such type of sand blasting. The method above outlined may be practiced by the use of an apparatus which may be moved over the area to be cleaned and having the necessary paraphernalia required for providing the sand blasting stream.

An apparatus particularly adapted for the carrying out of the above method may take the form of a self-propelled vehicle designated generally 10 and shown very conventionally in the drawings and which may be of any well-known manufacture, that shown being the usual so-called truck vehicle with the body removed therefrom. The vehicle has the usual wheels 11 on which is supported a chassis or frame 12 on the front portion of which is mounted the usual motor housing including the hood 13 which encloses the vehicle engine. The fuel supply or gasoline tank 14 may be mounted on the rear portion of the chassis at the location shown. It will be understood without further description that the vehicle 10 is to have all the necessary usual parts and controls, not shown, necessary to provide the proper operation of the vehicle.

Mounted on the chassis 12 in any suitable manner at the rear of the driver's seat 15 is a hopper 16 having a hinge closure 17. This hopper 16 may contain a supply of abrasive which may be the usual cutting sand or other suitable abrasive material employed in blasting operations. In the particular instance air is to be used as the carrier stream for the sand particles, and to this end a compressor 18 is mounted on the chassis 12 at a convenient location such as between the gasoline tank and the hopper 16. The compressor 18 has a supply conduit 19 which is of the usual flexible character and is controlled by a manual or otherwise operated valve device 20. Thus, the volume of air flow through the conduit 19 may be manually adjusted to that desired for particular conditions encountered in cleaning the road surface. This supply conduit 19 and a plurality of flexible sand conduits 21 from the hopper 16 each extend to the sand blasting nozzle

units designated generally 22. The nozzles 22 for convenience of illustration have tubular shank portions 23, each of which extends from a fitting designated 24 which may or may not be integral with the shank portion 23. The fittings 24 have a sand inlet 25 in the form of a short nipple to which may be connected the conduits 21. The fittings 24 are also provided with an air inlet conduit 26, each of which communicates with a common valve unit 27 which may be of a sleeve type rotatable to register simultaneously all of the conduits 26 with the air supply conduit 19. The valve is operated by means of a crank arm 28 attached to one end of the inner sleeve of the valve and may be spring biased, not shown, to be urged to the closed or off position thereof. The valve may be turned manually but preferably is turned to the on position by means of a hand-operated lever 29 which is pivotally attached intermediate the ends thereof to the sides of the chassis 12 adjacent to the seat 15 as at 30 whereby to be readily accessible to the operator when in the seated position. The lower arm 31 of the lever 29 is connected by means of a flexible cable or the like 32 to the said crank arm 28. Thus, by manually swinging the lever 29 in a clockwise direction it will through the cable 32 turn the crank arm 28 to move the valve to the on position so as to register the conduits 26 with the conduit 19, as previously described. The sand supply conduits 21 are attached to the inlets 25 of the fittings 24 whereby sand from the hopper will be conveyed to each of the fittings 24 to be picked up by the air flowing therethrough. The action of the air under pressure flowing through the fittings 24 will in a usual well-known manner draw sand to mix with the air stream to be projected under pressure through the jet end 33 of the nozzles 22.

The nozzles 22 and the parts attached thereto are supported on a cradle 34 which has an axle 35 at one end portion thereof on which are mounted wheels 36 for free rotation thereon. The front end portion 37 of the side frames of the cradle 34 converge toward each other and form spaced mounting eyes 38, a block 39 being positioned between the eyes 38 to maintain the same in the spaced relation. The cradle may be reinforced by a cross member 40 positioned at the forward end thereof providing triangulation with the converging portions. There is mounted on the axle 35 a support member or bracket 41 which is free to turn on the axle 35 and is provided with a plurality of grooves 42, one for each nozzle 22. The shanks 23 of the nozzles 22 rest in said grooves 42, and a clamp bar 43 is secured to the bracket 41 as by means of bolts 44 to securely fix the nozzles to the said bracket 41. It will be understood that the nozzles 22 may be slidably moved in the said grooves 42 for adjusting the same by unloosening the bolts 44 in a usual manner and then retightening the same. The bracket 41 is adjustably secured in a desired angular position by means of straps 45 secured to the end of the bracket and to the adjacent sides of the cradle 34. Thus, the angularity of the nozzles 22 to the road surface may be adjusted to that desired by a combined turning of the bracket of the axle 35 and sliding of said nozzle on said bracket 41 as previously described.

The cradle 34 is positioned at a location beneath the vehicle 10 to be substantially midway between the side frames of the chassis 12 and is pivotally secured to a post 46 which depends

from the chassis 12 to engage between the eyes 38 in register therewith to receive a pivot fastening 47. Thus, the cradle is pulled along the roadway by the vehicle 10, and the diameter of the wheels 36 determines the height at which the jet portion 33 of the nozzles 22 will be spaced from the road surface. The pivoting of this said cradle 34 will provide for the cradle to ride along any unevenness in road surfaces so as to maintain the nozzles 22 at the proper distance from the road surface.

It may be desirable to recover the spent sand and also the material removed from the road surface so that upon passing of the vehicle over the area of the road surface cleansed, the same will be free of such sand and removed material. To this end a receptacle 48 is provided. This receptacle has an open front side 49 which is positioned to be just ahead of the nozzle jet 33. The receptacle is mounted on the sides of the cradle as by means of pivoted links 50, best shown in Figure 1, to be suspended therefrom in such a manner that its center of gravity will cause the receptacle to swing about its pivot in a clockwise direction so that its front side will engage the road surface and follow any unevenness in road surface. The receptacle 48 is also provided with an opening 51 therethrough about which projects a short nipple to which is connected a return conduit 52 extending to the upper portion of the hopper 16 so that the spent material moved into the receptacle 48 will be moved upwardly through the conduit 52 to be deposited into the hopper 16. When certain conditions of oil, grease, and like deposits are such as to materially contaminate the sand supply should the same be returned thereto, then a separate collecting container, not shown, may be provided to which the conduit 52 may be attached.

It is also desirable for safety measures and also for confining the area being cleansed to provide a suitable shield, which in the instant disclosure is in the form of a bag or the like 53 which may be made of a canvas or other suitable material. The bag is closed at its upper end and suspended from the chassis 12 at a location to enclose the receptacle 48 and a portion of the jets 22, as best seen in Figure 1, openings 54 being provided in the sides of the shield 53 for the passage therethrough of the parts enclosed therein. The bottom and marginal portion of the bag is provided with a reinforcement 55 which may be of a heavy rubber or rubberized material whereby to weight the said shield 53 into engagement with the road surface.

The cradle is held in raised position when the vehicle is traveling from one area to another and is lowered at the area to be cleaned by means of a hand-operated lever 56 which is similar to the lever 29 and is pivoted as at 57 providing a lower arm portion 58, the end of which is connected by means of a cable or the like 59 to a crank 60 on a shaft 61 journaled in the sides of the chassis 12. Swinging the lever 56 in a clockwise direction will rock the shaft 61. The shaft is provided with crank arms 61 which are positioned directly above the sides of the cradle and connected thereto as by means of flexible cables 62. Thus, it will be seen that by swinging the lever 56, motion will be transmitted through the connection just described to raise the arms 61 and the cradle from the road surface and therewith the parts of the apparatus attached thereto, the weight of the cradle being sufficient to bias the same into

engagement with the road surface when the lever 55 is moved in the other direction. The present form of the invention is illustrated as being combined with a self-propelled vehicle. However, the same may take the form of a trailer-like vehicle to be attached to a self-propelled vehicle to be moved over the area to be cleansed. In other instances it may be found desirable to make the apparatus of a construction such that the cleansing nozzle may be manually moved over the area to be cleansed.

It will now be apparent that we have disclosed a method and an apparatus which will operate for the efficient removal of oil, grease, and like deposits which may be imbedded into the road surface.

We claim:

1. An apparatus for cleaning a road surface of oil, grease, and the like deposits thereon, comprising a wheeled vehicle, a cradle having one end portion thereof attached to said vehicle and the other end thereof adapted to engage a road surface to be moved therealong as drawn by said vehicle, a plurality of sand blasting nozzles adjustably mounted on said cradle to project therefrom at an angle to the road surface to direct a stream of abrasive under pressure against the said road surface to be cleaned.

2. An apparatus as set forth in claim 1 wherein said cradle is at a position centrally of the vehicle and beneath the same.

3. An apparatus as set forth in claim 1 wherein said cradle is provided with wheels for engaging the road surface.

4. An apparatus as set forth in claim 1 further comprising a shield surrounding said nozzles.

5. An apparatus as set forth in claim 1 further comprising means for raising said cradle from the road surface including a manually operated lever, and means connecting said lever to cradle 40 whereupon the swinging of said lever in one direction will raise said cradle from the road surface.

6. An apparatus as in claim 1 further comprising an open side receptacle positioned to be in front of said nozzle, and an outlet conduit from said receptacle whereby spent abrasive and matter dislodged from said road surface will be blown by said sand blasting stream into said receptacle and out through said conduit.

7. An apparatus for cleaning a road surface of oil, grease, and the like deposited thereon comprising a self-propelled motor vehicle having a chassis, a cradle having one end portion thereof pivotally mounted on said vehicle to be at a location beneath the chassis of said vehicle, the other end of said cradle being adapted to engage the road surface, means for raising said other end of the cradle from the road surface including a rockable shaft at a location above said cradle, flexible means connecting said shaft to said cradle whereupon rocking of said shaft in one direction will through said flexible means raise said cradle from the road surface, a plurality of sand blasting nozzles adjustably mounted on said cradle for directing a stream of abrasive on to the road surface to be cleaned, a hopper mounted on said vehicle for containing a supply of abrasive for said nozzle, and means carried by said vehicle for supplying a stream of fluid under pressure to said nozzle.

8. An apparatus as in claim 7 further comprising a valve for controlling the said nozzles and means including a manually operated lever for operating said valve.

9. An apparatus for cleaning a road surface of oil, grease, and the like deposits thereon, comprising a wheeled vehicle, a cradle having one end portion thereof attached to said vehicle and the other end thereof adapted to engage a road surface to be moved therealong as drawn by said vehicle, a sand blasting nozzle adjustably mounted on said cradle to project therefrom at an angle to the road surface to direct a stream of abrasive under pressure against the said road surface to be cleaned.
